UNITED STATES PATENT OFFICE.

CHARLES H. CORNELL, OF VALENTINE, NEBRASKA.

RAIL-FASTENING DEVICE.

1,244,707.

Specification of Letters Patent. Patented Oct. 30, 1917.

Application filed February 10, 1917. Serial No. 147,879.

To all whom it may concern:

Be it known that I, CHARLES H. CORNELL, a citizen of the United States, residing at Valentine, in the county of Cherry and State 5 of Nebraska, have invented certain new and useful Improvements in Rail-Fastening Devices; and I do hereby declare the following to be a full, clear, and exact description of the invention, such as will enable others 10 skilled in the art to which it appertains to make and use the same.

This invention is a rail fastening device for railroad tracks, and is designed more particularly as an improvement to the type 15 of rail fastening device disclosed in my former Patents No. 943,521 and No. 1,130,797. Heretofore it has been the practice when rails have become worn from long continued engagement with car wheel flanges, to re- 20 move the spikes or other retaining means, adjust the rails to restore the track to its proper gage, and to fasten the rails in their adjusted position by replacing the spikes or other retaining means in a new position on 25 the cross-tie. This operation consumes considerable time and is therefore very expensive.

With these conditions in view, the invention has for its object to provide a simple 30 and inexpensive fastening device to retain the rails of a railroad track upon the cross-ties thereof, and at the same time to provide means whereby the rails that have become worn on their inside edge through long con- 35 tinued engagement with car wheel flanges, may be shifted or adjusted inwardly to re-store the track to its proper gage by inter-changing or re-arranging certain parts of the device without changing the position of 40 the device relative to the tie, thereby elimi-nating the expense and time consumed in re-driving spikes, or applying the fastening de- 45 vice to the rail in a new position on the tie.

With these and other objects in view, that 50 may more fully hereinafter appear, the in-vention comprises a bolt of novel form, which may be provided with a cam element rotatably mounted thereon. The bolt may be so formed as to pass through a suitably 55 positioned aperture in a cross-tie, and en-gage suitable plates preferably positioned on the upper and lower faces of said tie, while the cam element engages a suitable portion of the rail, it being understood that coöpera-tive means may be employed between the

bolt and the lower plate to retain the bolt in operative position. One embodiment of the invention is hereinafter fully described, illus-trated in the accompanying drawings, and more particularly pointed out in the ap-pended claims, it being understood that such changes in size, proportion and minor de-tails of construction may be made as fall 60 within the scope of the appended claims, without departing from the spirit, or sacri-ficing any of the advantages of the inven-tion.

In the accompanying drawings:—

Figure 1 is a sectional view through a rail and cross-tie showing the invention applied thereto.

Fig. 2 is a plan view of the bolt with the cam mounted thereon.

Fig. 3 is a sectional view showing the bolt head and cam in detail.

Fig. 4 is a plan view of the lower plate showing the locking engagement between the bolt and the plate.

Fig. 5 is a view similar to Fig. 4, showing a modified form of locking engagement be-tween the bolt and the plate. Like reference numerals are used to designate like parts throughout.

In the embodiment of my invention dis-closed in the accompanying drawings, the 85 bolt 1 is preferably cylindrical in form and provided with a square-head 2, and termi-nates in a hook-member 3, the largest dia-meter of which is preferably the same as that of the shank of the bolt, as clearly shown in 90 Fig. 1. The hook 3 may be formed by mov-ing a gradually increasing amount of metal from the shank of the bolt beginning at a point substantially midway between the ends of the bolt and proceeding toward the lower 95 end, stopping abruptly at a suitable distance therefrom, thereby forming a lip 4. It is evident therefore that this lip may be formed by heating the bolt and drawing it out to the desired form, or the bolt and the 100 lip may be cast as one. If desired, the bolt may be provided with a plurality of lips, as shown in Fig. 5.

The device contemplates the use of two identical bolts, such as above described, the 105 bolt 1, designed to occupy the position on the inside of the rail, being provided with a spirally flanged cam 5, which is shown ro-tatably mounted upon the bolt adjacent the head thereof. The cam is preferably pro-

vided with a cylindrical collar 6, said collar being preferably of the same internal diameter as the cam, and of such external diameter as may be required for the purpose herein-
5 after explained.

The bolt 1, designed to occupy a position on the outside of the rail, is shown provided with a spirally flanged cam 7 rotatably mounted thereon, said cam being preferably of the 10 same size and shape as cam 5, but without a similar depending collar 6. A suitable plate 8 may be interposed between the rail 9 and cross-tie 10, and is preferably provided with a plurality of apertures 11 and 12. The 15 apertures 11 and 12, designed to lie on opposite sides of the rail 9, may be substantially of the same diameter as the bolts 1 and 1^a, and may have their centers spaced apart a distance equal to the width of the lower 20 rail flange, plus the diameter of a bolt, plus the thickness of the collar 6, assuming the bolts 1 and 1^a to be of the same diameter. The plate 8 may be provided with a plurality of relatively small apertures 19 positioned at a suitable distance from the apertures 11 and 12, and preferably between these apertures and the corresponding ends 25 of the plate 8.

The cross-tie 10 may be provided with a 30 plurality of apertures 13 and 14 preferably cylindrical and extending vertically through the tie, their axes passing through the centers of the apertures 11 and 12, respectively. The apertures 13 and 14 are designed to receive the bolts 1 and 1^a, and are preferably of a diameter substantially equal to that of the bolts.

On the underside of the tie 10 may be provided a suitable plate 16 having a plurality 40 of slots 17 coinciding with the apertures 13 and 14 of the tie 10. There may be provided a plurality of depressions 20 in the plate 16 adjacent the edges of the slots 17, and diametrically opposite each other at the 45 midpoint of the sides of the slots.

The cams 5 and 7 may be provided with suitable means, such as a plurality of slots or recesses 18, in their peripheries designed to receive a suitable tool, whereby the cams 50 may be rotated relative to the bolts. The operation of the device is as follows:—

The upper plate 8 is placed upon the tie so that the centers of the apertures 11 and 12 of the plate 8 coincide with the axes of the 55 apertures 13 and 14 of the tie. The rail is then placed upon the plate 8, so that the outside edge of the lower flange of the rail coincides with the inside edge of the aperture 12 of the plate, the inside edge of the flange falling a predetermined distance, the 60 thickness of the collar 6, from the inside edge of the aperture 13.

The bolts 1^a and 1, carrying their respective cams 5 and 7, are inserted in the apertures 13 and 14, respectively, the enlarged

collar 6 of the cam 5 simultaneously engaging the inner edge of the rail flange and the upper face of the plate 8.

The lower plate 16 is then applied to the tie, the bolts 1 and 1^a engaging the slot 17, 70 whereupon said bolts are rotated by means of a suitable tool applied to the square-heads thereof, thereby bringing the lips 4 of the hooked ends 3 into locking engagement with the depressions 20 of the plates 16. 75

Any suitable tool is then applied to the cams 5 and 7, and the cams thereby rotated relative to the bolts, thus bringing the spiral flange of the cams to bear with ever increasing pressure upon the rail flange. When the 80 cams have been rotated sufficiently to securely retain the rail in position, nails may be driven into the tie through the apertures 19 in the plate 8, hereinbefore referred to, and bent into engagement with one of the 85 slots 18 in said cams, thereby retaining them in their locked position.

When the rails thus laid become worn on their inside edges, due to the continued engagement of car wheel flanges, the track may 90 be restored to its proper gage by removing the bolts 1 and 1^a, and shifting the rail inwardly until the inside edge of the rail flange coincides with the inside edge of the aperture 13. The bolt 1^a carrying the cam 95 5 is then placed in the aperture 14 on the outside of the rail, the collar 6 engaging the rail flange and the upper face of the plate 8, and the bolt 1 is placed in the aperture 13 on the inside of the rail, whereby the rail 100 may be securely retained in its new position, as hereinbefore described. It is to be understood that the thickness of the collar 6 may be varied as occasion requires to permit of a greater or less adjustment of the rail. 105

In the practical application of this device, it is contemplated to shift the rails constituting one side of the track to restore the track to its proper gage at the first adjustment, and to shift the opposite rail inwardly 110 when it becomes necessary to adjust the gage of the track a second time.

Having thus fully described my invention, what I claim is:—

1. In a device of the class described, the combination with a rail and a tie, of a rail fastening device comprising a plurality of plates, a plurality of bolts to engage said plates, means on said bolts to rotatably engage the rail, and means to permit of the transverse movement of the rail on the tie without changing the position of the plates. 115 120

2. In a device of the class described, the combination with a rail and a tie, of a rail fastening device comprising a plurality of bolts, a plurality of plates, a plurality of spirally flanged cams rotatably mounted on said bolts, and means to permit of the transverse movement of the rail on the tie without changing the position of the plates. 125 130

3. In a device of the class described, the combination with a rail and a tie, of a rail fastening device comprising a plurality of plates, a plurality of hooked bolts to engage said plates when moved to a predetermined position, coöperative means carried by the bolt and one of said plates to lock the bolts relative to the plates, a plurality of spirally flanged cams rotatably mounted on the bolts and means carried by the bolts to permit of the transverse movement of the rail on the tie without changing the position of the plates.
4. In a device of the class described, the combination with a rail and a tie, of a rail fastening device comprising a plurality of plates provided with a plurality of apertures designed to coincide with a plurality of apertures in the tie, a plurality of bolts to secure said plates to the tie, means to lock said bolts relative to the plates, a plurality of spirally flanged cams rotatably mounted upon said bolts to engage the rail, and means carried by one cam to engage the rail and permit of the transverse movement of the rail on the tie without changing the position of the plates.
5. In a device of the class described, the combination with a rail and a tie having a plurality of apertures spaced apart a predetermined amount, of a plurality of plates provided with apertures to coincide with those of the tie, a plurality of bolts to engage said plates and secure the plates to the tie, means to lock the bolts relative to the plates, a spirally flanged cam carried by each of said bolts to engage the rail, a depending collar carried by one of said cams to engage the rail, means on the peripheries of the cams whereby the cams may be rotated relative to the bolts, and means to retain the cams in a predetermined position.
6. In a device of the class described, the combination with a rail and a tie provided with a plurality of apertures spaced apart a predetermined amount, of a plate designed to be interposed between the rail and the tie, said plate provided with a plurality of apertures to coincide with the apertures of the tie, a plurality of bolts to engage the plate and tie and extend therefrom, each bolt terminating in a plurality of hooks, a slotted plate to engage said bolts, a plurality of depressions in said plate adjacent said slots to form locking engagement with the bolts when the same are moved to a predetermined position, a spirally flanged cam rotatably mounted upon each of said bolts to engage the rail, and a depending collar carried by one of said cams to engage the rail and permit of its transverse movement on the tie without changing the position of the plates.

In testimony whereof I affix my signature, in presence of two witnesses.

CHARLES H. CORNELL.
